UNITED STATES PATENT OFFICE.

SVEN JOHAN NORDSTROM, OF SAN FRANCISCO, CALIFORNIA.

WRENCH.

1,360,670.

Specification of Letters Patent. Patented Nov. 30, 1920.

Application filed March 21, 1919. Serial No. 284,079.

To all whom it may concern:

Be it known that I, SVEN JOHAN NORDSTROM, a subject of the King of Sweden, and a resident of San Francisco, in the 5 county of San Francisco and State of California, have invented certain new and useful Improvements in Wrenches, of which the following is a specification.

The present invention relates to an improvement in wrenches, and more particularly to an improvement in wrenches for operating a valve provided with a relatively movable part, a valve of such construction being shown and described in the Nordstrom 15 Reissue Patent No. 14,516, reissued August 27, 1918.

The object of the invention is to produce a wrench of the above described type, and construct it in such manner that when it is applied to operating a valve or other member provided with a relatively movable part, the movable part may at times be moved relatively to the member and at other times the member and its part will be moved or turned 25 without relative movement. More specifically, the object of the invention is to produce a wrench for operating the valve of the said Nordstrom patent so that each time the valve is operated, that is to say, opened and closed, the screw for forcing the lubricant into the valve parts will be turned relatively to the valve plug so as thereby to lubricate the valve. To the accomplishment of this 30 object, the invention consists in the wrench described and claimed in the following specification:—

In the accompanying drawings illustrating the preferred form of the invention, Figure 1 is a section taken on the line 1—1 of Fig. 2; Fig. 2 is a top plan of the wrench as applied to the valve, the parts being shown at the beginning of the valve turning movement of the wrench; Fig. 3 is a view similar to Fig. 2 with the parts shown 45 at the beginning of the screw turning movement of the wrench; Figs. 4 and 5 are sections taken on the line 4—4 of Fig. 1 with the parts shown in the positions as indicated in Figs. 2 and 3 respectively; Figs. 6 to 8, 50 inclusive, show a modified form of the invention, Fig. 6 being a sectional side elevation, Fig. 7 a top plan, and Fig. 8 a section taken on the line 8—8 of Fig. 7; and Fig. 9 is a vertical section of a valve similar to 55 that shown in Fig. 1 of the said Nordstrom patent.

The wrench of the present invention is adapted for use in operating a turnable member or element having a part movable relatively to itself, where it is at times necessary or desirable to move or adjust the movable part relatively to the turnable member, and where at other times it is necessary or desirable to turn the member and part without relative movement between them. Such 60 construction and arrangement of elements is exemplified in the valve shown and described in the said Nordstrom patent and in the valve parts illustrated in the accompanying drawings. The valve parts necessary to 70 illustrate the function of the wrench of the invention comprise a tapered valve plug 9, hereinafter for convenience referred to as the valve, seated within a valve chamber 10, and having a valve stem 11, the upper end 75 12 of which is squared. The valve stem 11 is provided axially with a threaded hole 13 in which is received a lubricating screw 14 having a hole 15 in its upper end for the reception of a pin by which the screw may be 80 turned. Within the upper end of the tapered plug portion of the valve is a transverse hole 16 passing through the bottom of the threaded hole 13 and terminating at opposite points on the periphery of the valve. Channels 85 18 communicate with the hole 16 and with a chamber 19 formed at the bottom of the valve casing 20. The threaded hole 13 is filled with a lubricant before the screw 14 is inserted and when the latter is screwed 90 part way down into the hole the pressure on the lubricant forces it through the hole 16 down the channels 18 and into the chamber 19, thereby providing lubrication for the valve. When more lubrication is needed, the 95 lubricating screw 14 is turned. If at any time it is found that the valve is "frozen" in its seat, the lubricating screw is turned until enough lubricant is forced into the chamber 19 to lift the valve, as set forth and 100 more fully explained in said patent.

It has been found desirable in the operation of the above described valve to lubricate it each time the valve is opened and closed. This has heretofore been inconvenient of accomplishment where the valve is situated in a difficultly accessible place. To obviate this inconvenience, the wrench of the present invention has been provided, so constructed that when the wrench is manipulated to open and close the valve the lubricating screw is turned to force fresh lu- 105 110

bricant down the channels 18 on to the valve seat. The wrench shown in the form of the invention illustrated in Figs. 1 to 5, inclusive, comprises a handle 22, by which the 5 wrench may be manipulated, and a socket 23 adapted for engagement with the squared end 12 of the valve stem. As seen by reference to Figs. 2 to 5, inclusive, the wrench may be turned in either direction through 10 an arc of about 30° without turning the valve. During the valve closing movement of the wrench, the surfaces 24 of the wrench socket contact with the surfaces of the squared end of the valve stem, and during 15 the valve opening movement of the wrench the surfaces 25 of the wrench socket contact with the surfaces of the squared end of the valve stem.

This play or lost motion between the 20 wrench socket and the valve is availed of to turn the lubricating screw relatively to the valve during the operation of the valve. The screw may be turned in the valve either during the opening or closing movement. 25 In the arrangement of the parts shown in the drawings, the lubricating screw is turned in the valve during the valve closing movement of the wrench. For this purpose, the lubricating screw is provided with a 30 right-hand thread and this thread, for the greater part of its length, is provided with a series of teeth or notches 26 formed longitudinally of the screw, but which do not extend to the full depth of the thread, as clearly 35 appears in Fig. 1. It has been found that about a one-sixteenth turn of the lubricating screw forces out enough lubricant for a single lubrication of the valve and so there is conveniently provided sixteen teeth on the 40 periphery of the lubricating screw by which it may be engaged and turned. The teeth 26 are engaged by a pawl or spring pressed plunger 27 slidably received in a lug or housing 28 on the upper side of the wrench 45 socket. A spring 29 presses the toothed end 30 of the pawl toward and into engagement with the teeth 26. A pin 31 in the rear end of the pawl slides in a groove 32 in the lug 28 to prevent the pawl from turning. By 50 means of the pin the pawl may be disengaged from the teeth 26 so that the lubricating screw may be removed for the insertion of a fresh supply of lubricant. There may be any convenient number of teeth or notches 55 on the lubricating screw; if a greater or less number than 16 is employed, the number of degrees of play or lost motion between the wrench socket and the valve will be lessened or increased accordingly, in order to permit 60 the turning of the screw in the valve through at least the arc defined by one of the teeth or notches.

The valve is turned through 90° in one direction to open it and through 90° in the 65 opposite direction to close it. At the end of

the valve opening movement, the valve and wrench parts are left in the position indicated in Fig. 3. If, now, it is desired to close the valve, the wrench will be turned in a clockwise direction. The preliminary 70 turning movement of the wrench, that is to say, its manipulation through an arc of 30° in moving it from the position shown in Fig. 3 to the position shown in Fig. 2, does not turn the valve. This preliminary manipulation of the wrench does, however, advance the screw one tooth or notch so as thereby to lubricate the valve. It is thus seen that the valve is lubricated before its closing movement is begun. The further manipulation of the wrench through 90° closes the 80 valve, and during the closing of the valve there is no relative movement between the valve and the lubricating screw. When the wrench is manipulated to open the valve, it 85 first moves through 30° without turning the valve, and during this 30° of movement the pawl rides over the next succeeding tooth or notch into position to advance the lubricating screw one tooth on the next closing of 90 the valve. On the further turning of the wrench in an anti-clockwise direction, the valve, screw and wrench turn without relative movement between them into the position of Fig. 3. It will be observed that 30° 95 being one-twelfth of a circle, the movement of the wrench through its first 30° in its anti-clockwise direction is more than sufficient for the purpose of enabling the pawl to engage a fresh tooth, as shown in 100 Fig. 3. To lubricate the valve before the valve is opened, the lubricating screw would be provided with a left-hand thread and the teeth or notches 26 would point in the opposite direction. 105

If on attempting to close the valve it is found to be "frozen" in its seat, the wrench will be manipulated forward and backward a number of times through the preliminary 30° of screw turning movement until enough 110 lubricant is forced into the chamber 19 to free the valve in its seat.

The function and mode of operation of the form of wrench shown in Figs. 6, 7 and 8 are exactly the same as the function and 115 mode of operation of the form of wrench described above. In the modified form of the invention, a bushing 35 having a squared hole and a cylindrical exterior fits snugly over the squared end of the valve 120 stem and is fastened thereto by a set screw 36. The bushing is engaged exteriorly by the cylindrical socket 37 of the wrench, the handle of which is indicated at 38. The wrench socket fits the bushing loosely so 125 that it may turn easily thereon. From the top of the bushing rise two lugs or ears 39 and 40 which are adapted to be engaged by two lugs 41 and 42 formed on the top of the wrench socket. The wrench may be turned 130

30° in either direction before the lugs 41 and 42 engage with the lugs 39 and 40, as clearly appears in Fig. 7. On the lug 42 is a pawl housing 43, which houses a pawl arrangement like the form shown in Figs. 1, 2 and 3. By reference to Fig. 7, it will be seen that when the wrench is turned in a clockwise direction the first 30° of movement effects the turning of the lubricating screw 10 in the valve, then the remaining 90° of movement closes the valve. And, reversely, the first 30° of movement in an anti-clockwise direction causes the pawl to pass over the next succeeding tooth into position to 15 advance the lubricating screw one tooth on the next closing of the valve and the remaining 90° of movement opens the valve.

It will be understood that the invention may be embodied in forms other than those 20 shown and described and still be within the scope of the following claims.

Having thus described the invention, what I claim as new is:—

1. A wrench for operating a turnable member provided with a relatively-movable part comprising means for engaging the turnable member and means for engaging the relatively-movable part, said first named

means being provided with means for permitting lost motion between the turnable 30 member and itself when the latter is turned so that the relatively-movable part may be moved relatively to the turnable member.

2. A wrench for operating a turnable member provided with a relatively-movable 35 part, comprising a handle, a socket for engaging the turnable member and a spring-pressed pawl for engaging the relatively-movable part, said socket being provided with means for permitting lost motion between the turnable member and the socket 40 when the latter is turned so that the relatively-movable part may be moved relatively to the turnable member.

3. A wrench for operating a valve having a stem and provided with a screw having ratchet teeth, comprising a handle, a socket for engaging the valve stem and a spring-pressed pawl for engaging the ratchet teeth, said socket being provided 45 with means for permitting sufficient lost motion between the valve stem and the socket when the latter is turned so that the screw may be turned relatively to the valve.

SVEN JOHAN NORDSTROM.
